(57) **CLAIM**

The ornamental design for a cash box/security case, as shown and described.

DESCRIPTION

FIG. 1 is a perspective view of a cash box/security case with the handle in its retracted position showing our design;

FIG. 2 is a top plan thereof;

FIG. 3 is an elevational view of the front side thereof;

FIG. 4 is an elevational view of one side thereof;

FIG. 5 is an elevational view of the opposite side thereof;

FIG. 6 is an elevational view of the back side thereof;

FIG. 7 is a bottom plan view thereof;

FIG. 8 is a perspective view of the cash box/security case with the handle in its extended position; and,

FIG. 9 is a top plan view of the cash box/security case as shown in FIG. 8.

The circular slotted feature shown in phantom lines in FIGS. 1, 2, 3, 8, and 9 represents the portion of the design that forms no part of the claim.
